UNITED STATES PATENT OFFICE.

ROBERT LE ROY, OF BASIN, MONTANA.

ORE CONCENTRATOR.

1,421,264.

Specification of Letters Patent. Patented June 27, 1922.

Application filed April 15, 1921. Serial No. 461,501.

To all whom it may concern:

Be it known that I, ROBERT LE Roy, a citizen of the United States, and a resident of Basin, in the county of Jefferson and State of Montana, have invented a new and Improved Ore Concentrator, of which the following is a full, clear, and exact description.

This invention relates to an ore concentrator, and has particular reference to rocking concentrators.

An object of the invention resides in the provision of means whereby a concentrator trough is rocked by a suitable power mechanism to produce a highly efficient concentration of the ores with a minimum expenditure of time and labor.

Another object resides in the provision of means whereby the rocking of the trough is cushioned by suitable means in each direction of motion of the trough.

A further object resides in the provision of means whereby the concentrates can be very simply and efficiently removed.

25 A still further object resides in the provision of power means and transmission devices whereby the operation of the trough can be effected with a minimum expenditure of power.

30 In general, my invention comprises a concentrator trough which has a curved cross section and a bottom which is inclined downwardly toward the discharge end. The width of the concentrator from one end to the discharge end also increases. This concentrator is mounted on suitable bearings and adapted to be rocked by suitable power-crank connections. In its rocking motion in one direction and another, resilient cushioning means 35 are provided whereby the concentrator is returned to its normal position with a minimum expenditure of power on the part of the actuating mechanism.

40 A further feature resides in a plurality of guiding or funnel blades which are associated with one of the discharge outlets so as to facilitate the collection of floating concentrate and its guidance into the discharge outlet. Other features of the invention will 45 appear as they are set forth in the following description and claims and shown in the drawings.

The invention is illustrated in the drawings, of which—

55 Figure 1 is a plan view of the concentrator;

Figure 2 is a side view thereof;

Figure 3 is an end view of the concentrator;

Figure 4 is a vertical transverse section 60 taken on the line 4—4 of Figure 1; and

Figure 5 is an enlarged detail section of an outlet or discharge valve.

The preferred embodiment of my invention, as shown in the drawings, comprises 65 a concentrator trough which is adapted to be supported on a suitable base. This base is, as shown, preferably in the form of a rectangular frame comprising beams 1, 2 and 3 which at one end support a platform such 70 as 4. At the other end, the frame supports transversely extending joists or beams 5 and 6. On the ends of the beams 5 and 6 a pair of pulleys 7 connected to a shaft 7' are suitably mounted. Extending longitudinally of 75 the frame and above the same is a concentrator trough 8 made of any suitable metallic material. This trough has a curved cross section and an inclined bottom 9 which inclines downwardly from the left end to the 80 right or discharge end, as shown in Figs. 1 and 2. The upper edges of the open end of the trough are provided with reinforcing strips such as 10 and 11. Intermediate its length each of these strips is offset at 12 85 and 13 to provide a passage for bearing rods 14 and 15. These rods or bars 14 and 15 are circular in shape and are firmly gripped between the body of the trough 8 and the strips 10 and 11 to hold and support the 90 trough. The lower portions of these bearing bars are slightly spaced away from and encircle the under-surface of the trough and are adapted to bear on a plurality of idle rollers such as 16 which are disposed as indicated on the base frame. The bearing bars may be, in some other suitable fashion, connected throughout their lower length with the under face or under surface of the trough 8, if desired. Plates such as 17 and 18 close 100 the ends of the trough. In the plate 18 a discharge pipe 19 is suitably disposed. This pipe 19 is connected to a pair of fan-shaped blades 20 which extend therefrom in opposite directions, as shown, and are fastened as 105 at 22 and 23 to the inner surface of the trough. These blades, during the rocking of the trough, serve, as hereinafter indicated, as guiding means for the concentrate which may float on the surface of the fluid within 110 the trough.

A water inlet pipe 24 is suitably disposed

through the plate 18 and has on its inner end a perforated portion 25 through which water flows into the trough 8. Adjacent the lower portion of the plate 18 is disposed an outlet discharge valve plug 26 connected by suitable pipe such as 27 to the lowest level of the liquid in the concentrator trough 8. This valve plug is provided with a valve seat 28 adapted to receive a valve 29 which, on the side adjacent the trough, is provided with a stirring stem 30 and on the other side with a stem 31 the outer end of which, 32, is threaded to receive a hand wheel 33. The outer end 32 is provided with a turning bar 34. A spring 35 connects the hand wheel with a stationary lug 36 on the pipe 27. A sleeve 35', of any suitable material such as rubber, is provided between the hand wheel 33 and 20 the end of the plug 26 to provide a cushion therebetween. When the turning bar 34 is turned to rotate the stem 31 within the hand wheel 33, the valve 29 is unseated or seated in accordance with the movement 25 of the stem 31. The construction, however, is such as to permit the hand wheel to be moved to the right together with the stem 31 and the valve 29. This movement is for the purpose of moving the 30 end of the stem 30 to agitate any material which may have settled in the bottom of the trough adjacent the opening in pipe 27. This agitation is for the purpose of permitting the concentrate here located 35 to flow out through the discharge pipe 37.

The power shaft 7' is connected by a crank arm 38 with a connecting rod 39. At its other end this rod is connected to an adjustable block 40. This plug is adapted to be adjusted within a groove 40' located in a rocking bar 41. This rocking bar extends across the top of the concentrator trough 8 and is connected along a portion of its lower edge to a plate 42. This plate 42, at its end, is turned down and suitably connected, as by riveting, to the inner surface of the trough 8. The movement, therefore, of the power shaft through the crank mechanism just described will 45 cause the oscillation or rocking of the trough 8. At the discharge end of the trough or concentrator, adjacent the upper opposite edges, I have provided perpendicularly disposed parallel plates 43 between 50 which are disposed sloping tail or sluice gates such as 44 to provide for the overflow of suitable portions of the contents of the trough, as desired. A flanged connection bar such as 45 is applied to the 55 parallel surface of the rocking bar 41 and at its other end, such as 46, is connected to a shaft 46' extending across a part of a yoke frame. This yoke frame comprises parallel plates 47 between the ends of which 60 shafts such as 48 and 49 extend. These

shafts 48 and 49 receive the ends of springs such as 50 and 51, the other ends of which are suitably and fixedly fastened as at 52 and 53 to the base frame of the apparatus. These springs 50 and 51 are disposed on either side of the mid portion of the trough 8 to cushion the rocking motion thereof in either direction and to tend to restore the trough to normal at the end of each oscillation. 75

The material, such as ore, to be treated is placed in the trough and suitable liquid is introduced through the pipe 24 and under a desired pressure to cause the proper amount of circulation. Power is then applied to rock the trough through the crank mechanism above mentioned, whereupon the trough is rocked on the bearing rods 14 and 15 which roll on the idler rollers such as 16 above mentioned. As this rocking takes place, the settling out of the desired constituents slowly takes place. Certain of the material will float on the surface, and in this floating action it will be observed that the fan-shaped blades 20 and 21, disposed near the discharge end of the trough, will oscillate back and forth alternately above and below the surface of the liquid. In this way they will intermittently and more or less constantly interpose a barrier 90 between the tail or sluice gates 44 and the floating material and will tend to guide this material into the discharge pipe 19. Those portions of the treated material which settle to the bottom of the trough, 95 due to the inclination thereof, will move down toward the lower discharge end and will be disposed adjacent the outlet pipe 27. The lower outlet mechanism, described in connection with Fig. 5, can then be operated in the manner described to permit of the discharge of this material therefrom. 100

By reason of the inclination of the bottom of the trough, and by the extension of its width from the front to the rear end, it 110 will be observed that the smallest volume of liquid in the trough will be at the end furthest from the discharge and that the agitation at this smaller end is more violent than the agitation taking place at the other end, 115 which is the discharge end. This is more favorable to the operation of the device, since near the discharge end it is not desired to cause a large circulation, especially such as would affect the settling out of the 120 desired elements of the material being treated.

What I claim is:

1. A concentrator comprising a base frame, a concentrator trough disposed thereon, 125 bearing rods on the trough, rollers on the base adapted to receive the bearing rods, a source of power, connections between the trough and the source of power whereby the trough is rocked, and resilient cushion- 130

ing means connected to the trough and the frame to cushion the movement of the trough in either direction and restore the trough to normal at the end of each rocking stroke.

- 5 2. A concentrator apparatus comprising a base or support, a plurality of rollers on said support, a concentrator trough, a plurality of curved bearing rods disposed 10 around said trough at intervals, said bearing rods adapted to rest on the idle rollers, power means, connections between the trough and power means to rock the trough, and a pair of springs disposed on opposite 15 sides of the trough, one end of each spring connected to the base frame and the other end of each spring connected to the trough to cushion the movement thereof and restore the same to normal.
- 20 3. A concentrator which comprises a trough to be oscillated or rocked, a rocking bar fastened to and extending across the top of the trough, one end of the bar extending beyond the edge of the trough and having a 25 slot therein, a sliding block disposed in said slot, means for tightening the block in the slot as desired, a power shaft, and linkage between the block and the power shaft whereby the motion of the shaft will rock 30 the trough in a predetermined manner.

4. A concentrator which comprises a trough, a base frame on which said trough is mounted, curved bearing rods disposed on said trough at intervals throughout its length, a plurality of rollers disposed on 35 the base to receive the bearing rods whereby the oscillation of the trough can be effected, a pair of cushioning springs connected at one end to the base frame, a yoke frame disposed above the trough, the upper 40 end of each of the cushioning springs being connected to the yoke frame, and a flanged bar connected to the trough and pivoted to said frame, said spring affording cushioning means for the trough as it oscillates in one 45 direction and another.

5. A concentrator which comprises a trough to be oscillated, a rocker bar extending across the upper edge of the trough, means connected to the rocker bar for oscillating the same, a pair of cushioning springs fixed at one end to a suitable support, a yoke frame disposed above the trough and connected to the other ends of the springs, and a connection between the yoke frame and 50 the rocker bar whereby the motion of the rocker bar and the trough is cushioned by the spring.

ROBERT LE ROY.
